UNITED STATES PATENT OFFICE.

BERNARD MOSCHCOWITZ, OF NEW YORK, N. Y.

STAY FOR GARMENTS.

SPECIFICATION forming part of Letters Patent No. 386,714, dated July 24, 1888.

Application filed October 23, 1886. Serial No. 217,052. (No model.)

To all whom it may concern:

Be it known that I, BERNARD MOSCHCOWITZ, a citizen of the United States, residing at New York, in the county of New York and State 5 of New York, have invented new and useful Improvements in Stays for Garments, of which the following is a specification.

Heretofore stays for corsets, dresses, and underwear have been made by various methods, 10 among which may be mentioned a stay having its ends protected by metallic caps, the body of the stay being covered with a fabric, leaving the end caps exposed. These exposed caps are injurious to the material of the dress, cor- 15 set, or underwear, and, besides, are liable to become detached, thereby exposing the sharp ends of the steel, which cut the material of the garment.

The objects of my invention are to avoid the 20 above objections and provide a novel, efficient, and very durable stay for garments which can be applied to various garments without pro- 25 viding the latter with pockets, which I accom- plish in the manner and by the means here- inafter described and claimed, reference be- 30 ing made to the accompanying drawings, in which—

Figure 1 is a plan view of a stay embodying 35 my invention, omitting the external casing of textile material; Fig. 2, a similar view show- 40 ing the external casing applied to the covered and capped steel shown in Fig. 1; Fig. 3, a longitudinal sectional view on the line *x* *x*, Fig. 2; Fig. 4, a transverse sectional view on the 45 line *y* *y*, Fig. 2.

In order to enable those skilled in the art to 50 make and use my invention, I will now describe the manner of making the same, referring to the drawings.

The numeral 1 indicates a steel or similar 55 metallic stay, and 2 a covering of paper applied thereto and completely enveloping the stay, said paper covering consisting of a strip sufficiently wide to be folded around the stay 60 and have its edges overlap along the longitudi- 65 nal center of the stay. The paper covering at each side incloses a thin wire or fine cord, con- 70 stituting cores 4, which extend along the stay its entire length. The paper prior to its ap- 75 plication is furnished with an adhesive cement, 80 and after the paper has been folded around the stay the latter is passed between steel cylin- 85

ders under powerful pressure, the cylinders having annular ridges, whereby the paper is 90 pressed and compacted tightly upon the steel 55 stay, and the cores 4 at the edges are immov- 95 ably and firmly fixed in place, so that neither the stay nor the cores can move in any direc- 100 tion independent of the paper covering. The cylinders at the same time press together those 60 portions of the paper covering which are be- 105 tween the cores and the edges of the stay, thereby forming at each side a longitudinal 65 groove running the entire length of the stay between the cores and the edges of the steel, thus 70 producing a very compact stay with grooved 75 margins at each side between the cores and the steel that perfectly accomplish the designed 75 purpose, which is to avoid the necessity of pro- 80 viding or sewing stay-pockets on dresses, cor- 85 sets, and underwear to receive removable and 90 replaceable stays. The paper-covered steel is 95 now furnished with a metallic cap, 5, at each end, which caps have rounded outer edges, and 100 are subsequently covered and retained in po- 105 sition by the textile casing. The steel having 110 been covered by the paper strips and provided 115 with metallic end caps, which latter may be 120 fixed by pressure through the medium of me- 125 chanical devices, is finally incased by a strip of 130 textile fabric, 6—such as satin, cambric, or sat- 135 ine—which strip is folded around the paper- 140 covered steel with its edges meeting or over- 145 lapsing along the longitudinal center of the 150 stay. The strip of textile fabric is sufficiently 155 long to project beyond the stay, which can sub- 160 sequently be turned inward upon the body of 165 the stay to thereby confine the metal caps in 170 place and conceal or protect them, so that they 175 cannot become detached or injure the material 180 composing the dress, corset, or other garment.

The stay being cased with textile material, 185 as explained, is finally passed between the steel 190 cylinders, before explained, whereby the lon- 195 gitudinal grooves are formed in the same man- 200 ner that they are formed in the paper cover- 205 ing to the steel.

The stay thus constructed is provided with 210 a cored edging along each side, separated from 215 the steel by portions pressed into longitudinal 220 grooves, through which pass the threads for 225 sewing the margins of the stay to a dress, cor- 230 set, or other article, the edges being overstitched 235 upon the marginal cores, the stitching being

rendered very durable by the presence of the fine wires or cords constituting the cores, which latter preserve the entire marginal edges somewhat stiff and prevent the stitches from breaking away from the edge by distributing the wearing strain evenly along the entire margin. The longitudinal pressed grooves not only serve to provide narrow spaces between the cores and the steel for the passage of the stitches, but also stiffen and strengthen the stay and contribute to its wearing power or durability by distributing evenly along the length of the marginal edges the wearing strain of the stay.

Having thus described my invention, what I claim is—

A garment-stay consisting of a paper-covered steel and metallic end caps entirely incased by a strip of textile material, both the paper and the textile margins at the sides of ²⁰ the stay having internal cores, and each margin longitudinally grooved between its core and the edge of the steel, substantially as and for the purpose described.

In testimony whereof I have affixed my signature in presence of two witnesses. ²⁵

BERNARD MOSCHCOWITZ.
